UNITED STATES PATENT OFFICE.

FREE MOYNIHAN, OF CHICAGO, ILLINOIS.

INTERCHANGEABLE SIGN.

Application filed November 22, 1924. Serial No. 751,443.

My invention relates generally to interchangeable signs and more particularly to interchangeable signs having displaceable supporting units which may be positioned 5 to receive display material of a variety of sizes and kinds.

The primary object of the invention is a provision of an interchangeable sign which is adapted to display letters and pictures 10 of various dimensions.

Another object of the invention is a provision of a sign in which the subject matter may be easily changed.

A still further object of the invention is 15 the provision of an interchangeable sign which prominently sets forth the subject matter thereon both during the day and nighttime.

Further objects and advantages of my 20 invention will be obvious upon perusal of the accompanying drawing and this specification based thereon. It is to be understood, however, that this disclosure of my invention is given for purposes of illustration only and is not intended to unnecessarily limit the scope of the protection sought and defined in the claims.

That the invention may be better understood reference is had to the accompanying 25 drawing wherein

Fig. 1 is a front elevation of the device; Fig. 2 is a vertical transverse sectional view taken on the line 2—2 of Fig. 1;

Fig. 3 is a horizontal sectional plan view 30 on an enlarged scale as on the line 3—3 of Fig. 1;

Fig. 4 is a detailed fragmentary elevation illustrating the means for connecting the retaining frame to the body of the sign;

Fig. 5 is a detail perspective view, partially broken away, of one of the letter supporting units;

Fig. 6 is a similar view illustrating a modification of the construction disclosed in 45 Fig. 5;

Fig. 7 is a detailed perspective view of one of the letter blocks;

Fig. 8 is the plan view, a portion of which is broken away, of a modified form of sign 50 embodying the invention;

Fig. 9 is the vertical section on the line 9—9 of Fig. 8;

Fig. 10 is a rear elevation of the construction as shown in Fig. 8.

Referring to the drawings in detail, the 55 numeral 1 designates a reflector box which

comprises a substantially flat back portion having side walls integral therewith and extending at obtuse angles therefrom and adapted to properly distribute the light from 60 the illuminating element 2 over the face of the sign. To insure proper reflection of the light 1 the interior of the reflector box is enameled white. The illuminating element 2 comprises a socket 3 wherein the usual 65 electric light bulbs 4 are seated. Retaining members 5 and 6, affixed to the back of the reflector box, are employed for securing the illuminating element in position. A current supply conductor 7 is utilized for the light 70 bulbs 4. Ventilation is provided by the passage of air currents through holes 8 located in the side walls of the reflector box 1. Associated with the reflector box 1 is a base frame 9 which is retained in rigid relation 75 thereto by screws 10. Affixed to the base frame 9 is a supporting frame 11 which is secured thereon by screws 12. The said supporting frame 11 has a rabbet 13 around the inner perimeter thereof for the reception of 80 a light diffusing element 14, preferably in the form of translucent glass. The plate of said translucent glass is retained in position by anchor plates 15 which overlap the edges of said glass and also form a part of a supporting unit, as shown in Fig. 5, being fastened to the supporting frame 11 by screws 85 16. The supporting units referred to each comprise two or more supporting strips 17 and the rectangular anchor plates 15 referred to, which plates are attached to the ends of the supporting strips 17, preferably by soldering the same thereto. One of the plates 15 is applied to each end of a pair 90 of the strips 17, extending crosswise thereof, and is of sufficient dimension to afford a relatively large surface of contact with the supporting frame 11. The said supporting strips 17 are composed of two U-shaped channel members 19 positioned back to back, and a facing strip 20, the longitudinal marginal portions of which are bent over the 100 front flanges of the channel members giving a finished surface to the completed strip which is substantially H-shaped in cross-section.

The supporting units are arranged on the supporting frame 11 in such fashion as to accommodate the display matter to be mounted therein, and secured thereto by the 110 screws 16 which pass through the holes 18 provided in the anchoring plates 15. To

2 prevent the display matter from sliding endwise out of a supporting unit, a retaining frame 23 is provided which is rabbeted at its inner face and at the edge 24 to receive the end portions of the supporting units, and said frame 23 is mounted upon the supporting frame 11 and fastened thereto by the hooks 25. Each of said hooks is pivotally mounted on a screw 26 and adapted to engage a catch 27 as shown in detail in Fig. 4.

The letter blocks 21 shown in Figs. 1 and 7 are composed of a transparent substance, preferably plate glass, to which is affixed one 15 of the letters of the alphabet or group thereof. The said letters or group are composed of opaque substance, such as black paper, or they may be painted upon the glass. I have found that a very pleasing effect may be obtained when glass is used if the same is made translucent by sand blasting the surface thereof.

The sign is made up, after the supporting units have been attached to the supporting frame 11, by inserting the letter blocks 21 between the supporting strips 17 of the respective units, in accordance with the matter to be displayed. The retaining frame 23 thereupon is applied to the supporting frame 30 and fastened thereto by the hooks 25. When it is desired to display pictures, or other subject-matter than that formed by the letter display, a sufficient number of the supporting units may be omitted, and such 35 other matter is applied to the translucent panel 14 and suitably held in place thereon.

If it be desired to change the display effected by the letter blocks 21, it is merely necessary to remove the retaining frame 23, 40 after which the letter blocks may be removed endwise from the supporting units and changed to accord with the new subject-matter to be presented. This ready change of the letter blocks affords the highly desirable characteristic of interchangeability to the sign structure, and increases the latitude of its use for advertising.

When it becomes necessary to have access to the reflector box, as in the form shown in Figs. 1 to 7, inclusive, the retaining frame is removed and the screws 12 taken out, whereupon the supporting frame 11 may be taken off without disturbing the make-up of the sign and complete access had to the reflector box and illuminating element.

In the construction shown in Figs. 8, 9 and 10 rearwardly extending side walls 30 of the reflector box 31 have marginal portions 32 bent upon themselves. The marginal portions 33 being formed at an obtuse angle on back 34 are bent upon themselves similar to marginal portions 32 but oppositely disposed relative thereto and are adapted to slidably interfit therewith. Top wall 35 is provided with opening 36. Illuminating

element 37 is mounted in the back 34 and is withdrawn or inserted from the reflector box 31 thru opening 36 as permitted by the sliding arrangement of the back 34. Cover plate 38 is provided integrally with the back 70 34 and is formed at right angle to the same. A handle 39 is mounted on the cover plate 38 by which the slidable back 34 may be conveniently operated to withdraw or insert the illuminating element 37. Cover plate 38 is 75 slightly larger than opening 36. When the back 34 is in a closed position cover plate 38 will abut against wall 35 of the reflector box entirely covering opening 36 as indicated by dotted lines in Fig. 8 in which position illuminating element 37 will be properly positioned. A partially opened position of the back 34 is indicated by dotted lines in Fig. 9 and shows the illuminating element 37 about to pass thru opening 36.

It will be observed in the construction last described and illustrated in Figs. 8, 9 and 10, that the necessity of base frame 9 shown in Figs. 2 and 3 is dispensed with as the illuminating element is accessible from the back of the sign. The supporting frame 11 is therefore directly attached to reflector box 31 by screws 10.

The sign has the distinct advantage that the display material supporting units are displaceable and may be arranged to support letter blocks of practically any dimensions. Furthermore the sign shows up the material display thereon in an attractive manner and causes the same to stand out clearly during the daytime and the illuminating element 95 prominently sets it forth at night.

I claim:

1. In an interchangeable sign, the combination with a reflector box, of an illuminating element mounted in said box, a supporting frame mounted on said box, supporting units comprising a plurality of channel bars secured at their ends to anchor plates, said anchor plates being adapted to be displaceably mounted on said supporting frame, display material adapted to be inserted between said channel bars, and a retaining frame mounted on said supporting frame and adapted to cover the end portions of said supporting units.

2. In an interchangeable sign, the combination of a reflector box, means for illuminating said reflector box, a supporting frame mounted thereon, supporting units displaceably mounted on said supporting frame, display material adapted for insertion in and between said supporting units, and a retaining frame mounted on said supporting frame and covering the end portions of said supporting units.

3. In an interchangeable sign, the combination of a reflector box, an illuminating element mounted in said reflector box, a supporting frame mounted thereon, said sup-

porting frame being rabbeted around the inner perimeter thereof, a light diffusing element adapted to be mounted in the rabbeted portion of the supporting frame, supporting units displaceably mounted on said supporting frame, said supporting units comprising a pair of anchor plates and channel bars mounted thereon, display material adapted for insertion between said supporting units, and a retaining frame mounted upon the 10 said supporting frame and covering the end portions of the said supporting units.

In testimony whereof I have hereunto subscribed my name.

FREE MOYNIHAN.
